REFRIGERATOR CONTAINER

Donald W. Hill, St. Louis, Mo.

Application June 4, 1953, Serial No. 25,318

Term of patent 14 years

(Cl. D44—1)

FIG. 1.

FIG. 2.

FIG. 3.

Figure 1 is a side elevation of a refrigerator container illustrating my new design;

Figure 2 is a sectional view on the line 2—2 of Figure 1; and

Figure 3 is a fragmentary perspective view illustrating the corner post structure of the refrigerator container shown in Figure 1.

I claim:

The ornamental design for a refrigerator container, substantially as shown.
